FACE MASK FOR SWIMMERS

Samuel M. Davison, Evanston, Ill., assignor to Dacor Corporation, Skokie, Ill., a corporation of Illinois

Filed Apr. 16, 1964, Ser. No. 360,320

4 Claims. (Cl. 2-9)

My invention relates to face masks for underwater swimmers, more particularly to an improved face mask including improved means for facilitating the equalizing of the pressure in a diver's ears.

When scuba diving, swimmers each carry a supply of air, a pressure regulator and a face mask for covering the eyes and nose. The face mask usually consists of a generally tubular resilient member, one edge of which is contoured to sealably fit against the swimmer's face and surrounds and covers the nose and eyes of the swimmer to provide a water and air-tight seal. A transparent viewing window extends across the opposite side of the resilient member, and strap means attached to the resilient member are used to secure the mask in position on the swimmer's face. The air required by such an underwater swimmer is supplied through a hose leading from the air container to the regulator which may be located at the swimmer's mouth. The regulator controls the flow and pressure of the air which is supplied through the hose connection to the swimmer's mouth. The pressure at which air is supplied to the swimmer by the regulator is essentially the same as the ambient water pressure on the rest of his body. At times, however, the small passages in the swimmer's ears become blocked and the pressure therein thus differs from the ambient pressure as the depth of the swimmer changes.

Underwater swimmers are subject to varying pressures dependent upon the depth to which they dive. This pressure is particularly significant as it concerns the diver's ear drums. To prevent the increased pressure differential from puncturing or otherwise damaging the ear drums, the diver must be able to re-establish equilibrium between the exterior pressure of the water effective on the ear drum and the air contained in the diver's nasal and cranial passages.

Thus if a swimmer dives down to a selected depth, the pressure of the surrounding water may be momentarily higher than the pressure in the swimmer's nasal and cranial passages. To re-establish equilibrium of the external and internal pressure on the ear drums, the swimmer must "pop" his ears. In order to "pop" his ears, a diver closes his nose and forcefully attempts to exhale the air in his lungs. The stream of air flowing in his nasal and cranial passages creates a higher internal pressure and thus re-establishes pressure equilibrium on the internal and external sides of the ear drum.

Accordingly, it is a principal object of my invention to provide an improved face mask including means for enabling a swimmer to conveniently and easily "pop" his ears.

It is another object of my invention to provide an improved face mask having means for closing both nostrils of the swimmer's nose to permit "popping" of the swimmer's ears.

In the prior art some masks have been provided wherein the swimmer must use either his fingers or must manipulate the face mask in an abnormal position to close his nostrils in order to "pop" his ears. Since the swimmer may be engaged in other activities or his hands may be holding equipment, it is desirable for the swimmer to be able to plug or close his nostrils easily and with a minimum of effort.

It is accordingly yet another object of my invention to provide an improved face mask including means for enabling a swimmer to close both nostrils merely by pushing the face mask toward the top of his head.

2

In the attainment of the foregoing objects, I provide a face mask including means for permitting a swimmer wearing the mask to close or stop both nostrils concurrently merely by moving the face mask a slight amount. More particularly, I provide a face mask for swimmers including a pair of formed pads positioned on the resilient member, which pads are positioned immediately below the wearer's nostrils. To close the nostrils, the wearer merely pushes the face mask toward the top of his head whereby each pad contacts and closes a nostril whereby the swimmer can proceed to "pop" his ears.

Other objects and advantages of my invention will become apparent from the following description taken in connection with the accompanying drawings in which like reference characters refer to like elements throughout and in which:

FIG. 1 is a perspective view of a face mask in accordance with the invention. FIG. 1 includes the outline of a swimmer's face in order to more clearly show the relative position of the pads of the invention;

FIG. 2 is a top plan view of the pads of FIG. 1 to more clearly show the shape of the pads formed on the resilient member;

FIG. 3 is an end view taken along the lines 3-3 of the pads of FIG. 3 to show the height of the pads;

FIG. 4 is a top plan view of the pads according to the invention formed in an oval shape;

FIG. 5 shows a modification of the pads of FIG. 1 wherein both pads are formed on a same base; and

FIG. 6 is an end view of the pads of FIG. 5 taken along the lines 6-6 of FIG. 5 to show the height of the pads formed on the resilient member.

The embodiment of FIG. 1 shows a face mask 10 for underwater swimmers including pads formed and positioned in accordance with the invention. As shown, the face mask 10 includes a resilient member 11, such as of rubber, having an edge seal 12 (see FIG. 2). The edge seal 12 of the member 11 conforms to the contours of the swimmer's face, and is arranged to enclose the swimmer's eyes and nose. A viewing window 15 of glass, or like material, is affixed to the front portion of the face mask 10 and is clamped in place by a clamp 17 and the nut and bolt arrangement 18. The face mask 10 is affixed to the swimmer's head as by straps 13 which encircle the swimmer's head.

A pair of pads 21 and 22 preferably formed of relatively soft non-porous rubber, or the like, are positioned in the lower central part of the resilient member 11 and in a position immediately below the swimmer's nostrils. The pads 21 and 22 are arranged on the member 11 such that each pad is positioned immediately beneath a respective nostril, for purposes of being in position to close the swimmer's nostril, when desired, as will be explained more fully hereinafter.

The pads 21 and 22 are approximately an eighth of an inch in height and are formed, in plan view, as an egg-shape or ovoid as is better seen in FIG. 2. The pads 21 and 22 may also be formed in other shapes such as in an oval, as shown in FIG. 4 to be described hereinafter. In the particular embodiment of FIGS. 1-3, the dimensions of the ovoid pads are approximately three-quarter of an inch in the minor axis and approximately one and one-eighth inch in the major axis. The larger or base portion of the pads 21 and 22 is preferably positioned on the member 11 to be closer to the swimmer's face. A spacing 19 from about one-eighth to one-quarter of an inch is formed between the pads 21 and 22 to provide an area where the center portion of the nose between the nostrils

may rest. As better seen in FIG. 3, the pads 21 and 22, in the embodiment shown, are approximately one-eighth inch in height. The pads 21 and 22 may be affixed to the member 11 by any suitable means such as by glue 20.

When in use, the face mask 10 is adjusted on the swimmer's face such that the pads are approximately one-eighth to one-quarter of an inch below the swimmer's nostrils as shown in FIG. 1; in this position, the pads will not inhibit the flow of air from the nostrils. When the swimmer wants to "pop" his ear drums to equalize the pressure in his nasal and cranial passages with the ambient water pressure, as discussed hereinabove, the resilient member 11 of the face mask 10 is merely pushed upward (as oriented in FIG. 1), about a quarter of an inch such that the pads 21 and 22 close or seal the swimmer's nostrils. The swimmer can accomplish this conveniently and easily such as by pushing against the resilient member 11 or the mask 10 with one arm. Thus, even if the swimmer is holding any apparatus or if his hands are otherwise occupied it will not prevent the swimmer from being able to close his nostrils to "pop" his ears. When the pads 21 and 22 are in position closing the swimmer's nostrils, the swimmer can proceed to attempt to exhale the air in his lungs through his nose to "pop" his ears and thus equalize the pressure in his nasal and cranial passages with the ambient water pressure. After the swimmer has completed the act of "popping" his ears, the resilient member 11 of the face mask 10 adjusts or returns downward to the position shown in FIG. 1, and the swimmer can continue his activity.

FIG. 4 shows a pair of pads 21A and 22A according to the invention and formed in an oval shape. In the embodiment of FIG. 4 the dimensions of the oval are approximately one and an eighth inch in the major axis and about three-quarters of an inch in the minor axis. A spacing of about one-eighth to one-quarter of an inch is formed between pads 21A and 22A, and the pads are about one-eighth of an inch in thickness. The positioning of the pads 21A and 22A on the face mask and the means of utilizing these pads is the same as that for pads 21 and 22.

FIGS. 5 and 6 show another embodiment of the pads according to the invention. In this embodiment the two pads 23 and 24 may be of the same shape and size as are the pads shown in FIGS. 1-3. However, the pads 23 and 24 are formed on a single base 26; in effect, a thin strip 28 joins the two pads 23 and 24. This permits the two pads 23 and 24 to be formed as one piece. As in the embodiment of FIGS. 1 and 2, the same spacing 19 is provided to accommodate the central portion of the nose.

The construction shown in FIGS. 4 and 5 permits the two pads 23 and 24 to be more conveniently and easily positioned in the face mask 10. Merely by centering and positioning the one base piece 26 and gluing the base piece 26 on member 11, the pads 23 and 24 are correctly positioned in the face mask 11. The pads 23 and 24 of

FIGS. 4 and 5 are utilized in the same manner as pads 21 and 22 of FIGS. 1-3.

Although I have herein shown and described specific forms of apparatus embodying my invention, it will be understood that various changes and modifications may be made therein within the scope of the appended claims without departing from the spirit and scope of mind. Having thus described my invention, what I claim is:

1. A face mask to be worn by underwater swimmers comprising, in combination, a resilient member formed to surround the wearer's eyes and nose and having one continuous edge thereof conforming to the wearer's face, a viewing window positioned over an opposite continuous edge of said member, two individual, raised, resilient and imperforate pads positioned on said member so as to be free of connection with each other and spaced apart at least one-eighth of an inch between each other, said pads being formed in the shape of ellipses having a minor axis of at least three-quarters of an inch and having a major axis of at least one and one-eighth inches, said pads being at least one-eighth of an inch thick, whereby said pads conform to a wearer's nostrils to thereby permit closing of both nostrils concurrently.
2. A face mask as in claim 1 wherein said resilient member is formed of an elastomeric material.
3. A face mask as in claim 1 wherein said pads are mounted to said member by a flat base piece having one of its flat surfaces affixed to the lower central portion of said member in a position immediately below the swimmer's nostrils and having said two individual pads affixed to its other surface in spaced-apart relationship.
4. A face mask to be worn by underwater swimmers comprising, in combination, a resilient member formed to surround the wearer's eyes and nose and having one continuous edge thereof conforming to the wearer's face, a viewing window positioned over an opposite continuous edge of said member, two individual, raised, resilient and imperforate pads positioned on said member in spaced relation to one another, said pads being free of connection with each other and being spaced at least one-eighth of an inch apart, said pads being positioned in the lower central portion of said member to be in a position immediately below the wearer's nostrils, said pads each being ovoid in plain view and dimensioned to be at least one and a quarter inches in the major axis and at least three quarters of an inch in the minor axis.
